GEORGE W. CHANDLER, OF MANHATTAN, KANSAS, ASSIGNOR OF ONE-HALF
TO WILLIAM C. SNOW, OF BOSTON, MASSACHUSETTS.

MAGAZINE-FIREARM.

SPECIFICATION forming part of Letters Patent No. 632,235, dated September 5, 1899.

Application filed October 5, 1893. Serial No. 692,702. (No model.)

To all whom it may concern:

Be it known that I, GEORGE W. CHANDLER, a citizen of the United States, residing at Manhattan, in the county of Riley and State of Kansas, have invented new and useful Improvements in Firearms, of which the following is a specification.

My invention relates to magazine-firearms, and has for one of its objects to provide such a firearm embracing a plurality of cartridge-chambers arranged to supply a common race and means for preventing the cartridges in the several chambers from interfering with or crowding the cartridges passing up the race, and thereby rendering the mechanism inoperative.

Another object of the invention is to provide a magazine-firearm embracing a plurality of cartridge-chambers so constructed that they may be simultaneously increased or diminished in length by the movement of a single part to adapt the gun to fire cartridges of different lengths.

Another object is to provide a magazine-gun the mechanism of which is as a whole simple, compact, and durable and is therefore not liable to get out of order in use.

Other objects and advantages of the invention will be fully understood from the following description and claims when taken in conjunction with the annexed drawings, in which—

Figure 1 is a longitudinal section of a portion of my improved firearm with the shutter of the magazine-chamber and the shutter of one of the subchambers shown as open. Fig. 2 is a detail longitudinal section with the breech-bolt in its retracted position. Fig. 3 is a transverse section taken in the plane indicated by the line 3 3 of Fig. 1. Figs. 4, 5, and 6 are enlarged transverse sections taken in the planes indicated by the lines 4 4, 5 5, and 6 6, respectively, of Fig. 1. Fig. 7 is an enlarged detail longitudinal section taken in the plane indicated by the line 7 7 of Fig. 1. Fig. 8 is a similar view taken in the plane indicated by the line 8 8 of Fig. 1. Fig. 9 is a detail longitudinal section illustrating the pinion for transmitting motion from the reciprocating operating-slide to the cartridge-feed bar. Fig. 10 is a transverse section taken in the plane indicated by the line 10 10 of Fig. 2.

In the said drawings similar letters designate corresponding parts in all of the several views.

My improved firearm embraces a barrel A and stock B of common form and is provided with the usual opening a for the escape of empty shells and the usual breech-bolt C for shoving cartridges into the breech end of the barrel as the cartridges are presented and closing said breech. The breech-bolt is arranged in a suitable guideway and is moved through the medium of a reciprocating operating-slide D, with which it is connected by a latch E, as best shown in Fig. 9. Said latch is in the form of a bell-crank lever, and it is fulcrumed at b in a recess in one side of the breech-bolt and comprises a rear arm c, having a lateral branch c', and a forward arm d, having a lateral branch e. Incident to the forward movement of the breech-bolt C and slide D the latch E rests in the position shown in Fig. 2—that is to say, the branch e of the arm d rests in a notch f in operating-slide D and the branch c' of arm c rests on a longitudinal ledge or bearing g. Now when the operating-slide D is moved forward the arm c of the latch resting on the bearing g will prevent the arm d from rising out of the notch f of the slide, and in consequence the bolt will be carried forward with the slide. The parts are so arranged that the operating-slide D has a slight forward movement after the breech-bolt has assumed its closed position, and the ledge or bearing g is of such a length that the latch-arm c will reach the forward end thereof coincident with the bolt reaching its closed position. Such slight forward movement of the operating-slide D after the breech-bolt has reached its closed position operates to depress the arm c of the latch and enables said arm to engage the end of the ledge or bearing g, and thereby lock the bolt in its closed position. When the operating-slide D is moved rearward to open the breech, it will first rock the latch E to raise the arm c thereof upon the ledge or bearing g and release the bolt, and will then move the latch and the bolt rearwardly. The breech-bolt is provided with an ordinary or other suitable

cartridge-extractor *h*, adapted to operate incident to its rearward movement, and it is also provided with an ordinary firing-pin *i*, the same being arranged to be struck by a hammer *j*, controlled by the usual sear *k* and trigger *l*.

F is the magazine-chamber, which is formed in the rear portion of the stock and is designed to be normally closed by a shutter *G*, disposed at one side of the same. In the said chamber *F* are three (more or less) subchambers *H*, designed for the reception of vertical tiers of cartridges after the manner shown in Fig. 1. These subchambers *H* in the preferred embodiment of the invention are formed by slightly-curved rear walls *m*, slightly-curved forward walls *n*, and shutters *p*. The rear walls *m* are fixed to the side wall of the chamber *F*, while the forward walls *n*, which are preferably channeled to better hold the forward ends of the cartridges against lateral deflection, are carried by a slide *I*, which is arranged in a guideway *q* in the wall of chamber *F* and is designed to be adjustably fixed in position by a thumb-screw *r* or other suitable means. By reason of this construction the length of the subchambers *H* may be readily increased or diminished to enable them to receive and properly guide and deliver cartridges of various lengths to the race leading up to the barrel of the gun. This is obviously an important advantage, since it permits of the use of cartridges of various lengths in the gun. I prefer to fix the rear walls *m* of the subchambers *H* with respect to the stock as shown and described; but it is obvious that when desired the front walls may be fixed and the rear walls made adjustable to increase or diminish the length of the subchambers.

The shutters *p* of the subchambers are connected in a hinged manner to the stock *B*, so as to enable them to swing downwardly and outwardly, and they are designed to be secured in their closed position by suitable latches *s*, as shown. At their inner sides they are each provided with spring-backed plungers or followers *t*, which have for their purpose to press the cartridges downwardly and positively feed the same to the race.

J is the race, which is disposed below the several subchambers *H* and extends up to the breech end of the barrel, as shown.

K are spring-pressed beveled detents, which project up from a fixed part *K'* of the stock, which forms a portion of the floor of the race, at points below the rear walls *m* of the subchambers *H* and at corresponding intervals along the forward portion of the race, and *L* is a reciprocatory cartridge-feeding bar, which is arranged alongside of and flush with the fixed part *K'* of the stock and forms part of the floor of the race *J* and is provided at intervals with spring-pressed beveled detents *M*. The detents *M* of the reciprocatory bar *L* are so disposed that when said bar is in its lowermost or rearward position they will each

rest slightly in rear of one of the stationary detents *K*, and when said bar is moved forwardly to the full extent they will assume positions slightly forward of the next forward stationary detents. It follows from this that with the several subchambers *H* filled with cartridges and the lowermost cartridges bearing at their heels against the stationary detents 75 below the walls *m* of the subchambers *H* a full forward movement of the feed-bar *L* will carry each of the lowermost cartridges forwardly from one detent *K* to the next forward detent *K*. In this way the cartridges are fed 80 in succession and step by step toward the breech end of the barrel. The final movement of the cartridges—that is to say, the movement from the forward stationary detent *K* to the breech end of barrel *A*—is effected by the spring-pressed tongue *N* on the feed-bar *L*, the said tongue, like the detents *K* *M*, being adapted to yield and allow the cartridges to pass over it and then spring up and engage the rear end of the cartridges 90 after the manner shown in Fig. 2. By reason of the feed-bar *L* being arranged flush with the fixed part *K'* of the stock and serving in conjunction with the same to form the floor of the race it will be seen that said feed-bar does not take up any part of the race and consequently permits of said race being made of a size but slightly larger than the diameter of the cartridges. It will also be observed that by reason of the sets of detents *K* and *M* being both arranged at the lower side of the race gravity assists the cartridges in remaining in position in advance of said detents.

In order to prevent the cartridges in the several subchambers *H* from interfering with or crowding the cartridges passing up the race *J* and thereby rendering the mechanism inoperative, I provide hinged or pivoted gates *P* at the lower ends of the rear walls *m* of the two forward subchambers *H*. These gates *P* when the subchambers *H* are filled with cartridges rest in a pendent position and consequently do not interfere with the lowermost cartridge of each tier assuming a position on the floor of the race *J* and against a detent *K* projecting therefrom. When, however, the feed-bar *L* is moved upwardly and forwardly, the cartridges that were the lowermost of the rear and middle tiers will assume a position 120 below the middle and forward tiers, respectively, and in so doing will press the gates *P* of said middle and forward tiers forwardly and upwardly into a horizontal position and in that way trap the cartridges in the middle 125 and forward compartments. At every forward movement of the feed-bar *L* a cartridge will be placed below the gates *P*, and hence it will be seen that cartridges will be effectually prevented from leaving the middle and forward chambers *H* until the rear chamber is exhausted and that cartridges will be effectually prevented from leaving the forward chamber *H* until the middle chamber *H* is ex-

hausted. It follows from this that the cartridges will be fed in regular succession from the rear chamber, from the middle chamber, and from the forward chamber in the order named, and in consequence there is no liability of the cartridges getting in the way of or interfering with the movements of each other and there is also no liability of any cartridge assuming or being thrown into such a position as to interfere with the proper working of the mechanism of the gun.

For the purpose of holding the cartridges a proper distance apart, and this notwithstanding the momentum which is imparted to them by the forward throw of the feed-bar L, I provide the upper wall of that portion of the race J in advance of the subchambers H with spring-pressed shoes Q, which, impinging against the cartridges, serve to prevent them from moving a greater distance than the throw of the feed-bar and serve to insure them always resting the proper distance apart.

The operating-slide D before described is disposed at one side of the longitudinal center of the stock B and is steadied in its movements by a guide-bar V at the other side of the longitudinal center, to which it is connected by a hand-grip W, as shown. It serves, as stated, to transmit reciprocatory motion to the breech-bolt C and is provided with a rack portion w, between which and a similar rack portion x on the feed-bar L is interposed a pinion y, as best shown in Fig. 9. From this it will be seen that the slide D serves to transmit reciprocatory motion to the cartridge-feeding bar as well as to the breech-bolt; also, that the movements of the breech-bolt and cartridge-feeding bar will be in opposite directions—that is to say, when the breech-bolt is moved rearwardly the feed-bar will be moved forwardly and when the breech-bolt is moved forwardly the feed-bar will be moved rearwardly.

The operation of my improved magazine-gun will be fully understood from the foregoing and need not be repeated in detail. Suffice it to say that with the subchambers H filled with cartridges the gun may be fired very rapidly, it being simply necessary to reciprocate the hand-grasp W after a shot is fired in order to eject the empty shell, place a fresh cartridge in the barrel, and lock the breech-bolt in its closed position. It will also be noticed that the gun may be very expeditiously charged with cartridges, it being simply necessary to raise the shutter G and release and swing the shutters p downwardly and place the cartridges in the subchambers H. With this done the shutters p are raised and fastened and the shutter F closed and fastened, when the gun is ready for use.

I have entered into a specific description of the construction and relative arrangement of the parts of my improved firearm in order to impart a full, clear, and exact understanding of the same. I do not desire to be understood, however, as confining myself to

such specific construction and arrangement of parts, as such changes and modifications may be made in practice as fairly fall within the scope of my invention.

Having thus described my invention, what I claim is—

1. In a firearm, the combination of a barrel, a stock having a magazine-chamber and a race arranged to receive from said chamber and leading to the breech end of the barrel and also having a fixed portion K' forming a part of the floor of the race and having recesses in its inner edge at intervals in its length, yielding detents arranged in said recesses of the stock portion K' and projecting up into the race, a reciprocatory bar arranged alongside of and flush with the stock portion K' and forming part of the floor of the race and having recesses in its inner side at intervals in its length and yielding cartridge-engaging devices in said recesses normally projecting above the floor of the race, and an operating-slide connected with said reciprocatory bar, substantially as specified.

2. In a firearm, the combination of a barrel, a stock having a magazine-chamber and a race arranged to receive from said chamber and leading to the breech end of the barrel and also having a fixed portion K' forming a part of the race and having recesses in its inner edge at intervals in its length, yielding detents arranged in said recesses of the stock portion K' and projecting up into the race, a reciprocatory bar arranged alongside of and flush with the stock portion K' and forming part of the floor of the race and having recesses in its inner side at intervals in its length and yielding cartridge-engaging devices in said recesses normally projecting above the floor of the race, yielding shoes disposed at intervals in the upper wall of the race between the magazine and breech end of the barrel, and an operating-slide connected with the reciprocatory bar, substantially as specified.

3. In a firearm, the combination of a barrel, a stock having a magazine-chamber and a race arranged to receive from said chamber and leading to the breech end of the barrel and also having a fixed portion K' forming a part of the floor of the race and having recesses in its inner edge at intervals in its length, yielding detents arranged in said recesses and projecting up into the race, a reciprocatory bar arranged alongside of and flush with the stock portion K' and forming part of the floor of the race and having recesses in its inner side at intervals in its length and yielding cartridge-engaging devices in said recesses normally projecting above the floor of the race, yielding shoes disposed at intervals in the upper wall of the race between the magazine and breech end of the barrel, a reciprocating breech-bolt, a fixed bearing, an operating-slide having a notch and also having a rack, a rack on the reciprocating bar, a pinion arranged between and meshing with the racks of the reciprocating

bar and operating-slide, and a latch pivotally connected to the breech-bolt and having an arm arranged in the notch of the slide and another arm arranged to engage the fixed bearing, substantially as specified.

4. In a firearm, the combination of a plurality of cartridge-receptacles, a race arranged to receive from said receptacles, means for moving cartridges along the race, and mechanism, operated by the advancing cartridges from one receptacle, for holding the cartridges in the other receptacle until the first-named receptacle is depleted, and then releasing the cartridges in such other receptacle, substantially as specified.

5. In a firearm, a plurality of cartridge-receptacles disposed one in front of the other, a race arranged to receive from said receptacles, means for moving cartridges along the race, and a gravitating support, operated by the passing cartridges from the rear receptacle, for holding the cartridges in the forward receptacle until the rear receptacle is depleted and then releasing the cartridges in the forward receptacle, substantially as specified.

6. In a firearm, the combination of a barrel, a stock having a plurality of cartridge-receptacles arranged one in front of the other, a race disposed below and arranged to receive from said chamber and leading to the breech of the barrel, yielding devices projecting up from the floor of the race at intervals in the length thereof, a reciprocating feed-bar arranged flush with the floor of the race and having yielding cartridge-engaging devices at intervals in its length, an operating-slide connected with said feed-bar, a breech-bolt, means controlled by the slide for locking said bolt in its closed position, and a gravitating

support, operative by the passing cartridges from the rear receptacle, for holding the cartridges in the forward receptacle until the rear receptacle is depleted and then releasing the cartridges in the forward receptacle, substantially as specified.

7. A firearm embracing a plurality of cartridge-receptacles arranged in its stock and comprising walls fixed with respect to the stock, and opposite walls carried by a common slide adjustably fixed with respect to the stock whereby the size of the several receptacles may be simultaneously and correspondingly increased or diminished in size, substantially as specified.

8. A firearm embracing a magazine-chamber arranged in its stock, a shutter therefor, and a plurality of subchambers arranged in the magazine-chamber; each of the said subchambers having one of its walls adjustably connected to the stock and also having a shutter connected to the stock and carrying a spring-backed follower, and means for holding the shutter in its closed position, substantially as specified.

9. In a firearm, a stock, having a cartridge-receptacle one of the end walls of which is adjustably connected to the stock and movable toward and from the other end wall, whereby said receptacle may be increased or diminished in length, substantially as specified.

In testimony whereof I have hereunto set my hand in presence of two subscribing witnesses.

GEORGE W. CHANDLER.
